[57] ABSTRACT

This invention relates to simple type of honing tool for accurately finishing the interior surface of a cylindrical hole in a work piece. It has contained within its body portion and electronic device with means to measure and control the degree of a predetermined amount of finish to the workpiece and to shut off the power when the desired degree of finish is obtained. Another feature of this improved honing tool is that its construction is such that it may be used to finish the interior surface of blind holes in a workpiece.

HONING MANDREL

This application is continuation in part of my copending application Ser. No. 631,115, filed Apr. 12, 1967, now abandoned.

This invention describes honing mandrels which are tools to be used with a production type of honing machine not a part of this invention, which machine will apply rotational and longitudinal motion to the honing mandrel. This invention relates to a honing tool of simple construction and provides a means of quick change of honing abrasive without the use of any type of tools by the releasing of a pair of resilient members.

A feature of this invention is the provision of a cavity within the honing mandrel for retaining an electronic device to control and indicate the degree of metal removed on the interior surface of a workpiece without removing the mandrel from the production type of honing machine.

This invention relates to machine tools and more particularly to a honing mandrel for use in a honing machine which provides rotational and longitudinal or forward motion during the production of the honing operations, which mandrel is of relatively simple construction and yet, gives a fine finish of the interior surface of a workpiece or device to be honed while at the same time maintaining extremely close tolerance.

It is an object of the present invention to provide a simple honing mandrel which may be interchangeably mounted in existing honing machines without modification of such machines.

Heretofore, many different types of honing mandrels have been proposed and many of these were objectionable, in that, they were extremely complicated and difficult to provide parts of sufficient strength to withstand vibration and wear and furthermore, the abrasive holder size of such prior art mandrels was limited by the size of the housing and component parts. Difficulty was likewise experienced in previous mandrels in the changing of the abrasive members, in maintaining accurate adjustment of the abrasive members and, in certain designs such abrasive members tended to move radially outward from the mandrel when the same was withdrawn from an internal surface of a workpiece due to the centrifugal forces set up by speed and rotation of the mandrel.

Another object of this invention is to provide a mandrel which provides quick means of changing abrasive members without the use of tools by the release of a pair of resilient members.

A still further object of the invention is the provision of a honing mandrel which provides a three point contact with the interior surface of the aperture in a workpiece to be honed.

Another object of this invention is the provision of a cavity within the body member of the honing mandrel for retaining an electronic device to control and indicate the degree of metal removed on the interior surface of a workpiece without removing the mandrel from the production type of honing machine.

Another object of the invention is the provision of a honing mandrel in which adjustment of an abrasive member or members may be accomplished by longitudinal or forward movement of the mandrel with relation to such an abrasive member, there being provided cooperation wedged surfaces and resilient means for holding such surfaces in working engagement, thereby maintaining a proper adjustment of the abrasive member.

Another object of the invention is the provision of a honing mandrel in which adjustment of an abrasive member may be accomplished by movement of the wedge with relation to the abrasive member by the provision of cooperating cam surfaces and resilient means for holding such surfaces in operative engagement, with a workpiece.

A still further object of the invention is the provision of a honing mandrel in which all of the parts fit together relatively tight in relationship order to maintain accurate adjustment and also to prevent undue centrifugal vibration or chatter due to the outward displacement from center of the adjusting member thereby resulting in an extremely smooth or fine finish to the interior honed surface, as well as an accurate diameter.

A still further object of the invention is the provision of a honing mandrel in which a cam is provided in the mandrel and in which spaced surfaces are provided on cage ends at spaced intervals for holding the abrasives and guide blocks, which spaced surfaces cooperate with the cam surfaces to maintain the stone and guide blocks in accurate alignment and thus prevent tilting or undesired movement thereof, other than in the desired radial direction.

A still further object of the invention of the provision of a honing mandrel for blind holes, in which adjustment of the abrasive member is accomplished by movement of a cam bar and is maintained against relative movement with respect to the mandrel and the cam member.

A further object of the mandrel of this invention is to provide a space within the body portion for retaining electronic means for automatic size control also to provide a remote size measurement remote from the mandrel.

A further object of the mandrel is to provide a space within the mandrel for an electronic and automatic size control for the remote reading of size measurement by means of a cam actuated linkage and an electronic member such as for example a variable capacitor or an inductance which changes the frequency of a tuned high frequency circuit.

A further object on the mandrel is to provide a housing in which electronic means provides automatic size control device and a remote meter reading means to measure the amount of metal removed on a workpiece.

A further object of the mandrel is to provide an easily manufactured housing for automatic size control device whereby internal diameter measurement is made by connecting the electronic means by conductors attached to and connected with collector rings on the mandrel.

Further objects and advantages of the invention will be apparent from the following description taken in conjunction with the accompanying drawing wherein:

FIG. 1 is a longitudinal view partly in section showing the mandrel of this invention.

FIG. 2 is a rear end view partly in section of FIG. 1.

FIG. 3 is a cross section of FIG. 1 taken on line B.

FIG. 4 is a sectional elevation, the section being taken on line B of FIG. 1 with the guide members removed.

FIG. 4A is an enlarged section of an end portion of FIG. 4.

FIG. 5 is a circuit diagram showing the use of the electronic device of this invention in the form of a variable condenser.

FIG. 6 is another circuit diagram showing the use of a variable inductance as the electronic device.

Referring now in detail to FIG. 1 of the drawing, 1 is the main mandrel supporting body the forward end portion having engaging means indicated by lines A and B, C and D for securing the mandrel of this invention in a honing machine which machine is the type used for honing workpieces in production and is not part of this invention. The honing production machine provides both rotational and longitudinal or forward movement to the mandrel of this invention. 1A is the rear end portion of supporting body 1 which supports rods 3, 3A, and 3B. Guide members 3C shown in section in FIG. 3 are interposed between rods 3, 3A, and 3B and nested in with the honing abrasive members. Three slots 1B are also located at the end portion 1A of the body member 1. The wedged discs 2 and 2A each have a serrated edge for their free passage on the rods 3, 3A, and 3B. Part 4 is a dislodge end member having three angular slots or grooves 1C similar to the slots 1B located at the end portion 1A of member 1. 5 is the central threaded rod or central control member by which longitudinal or forward movement from the production honing machine is applied by the forward end of engaging member 5A. Part 6 indicates the retaining springs or "O" rings for entry into grooves 1D and 6A. The end of rod 5 opposite engaging member 5A is provided with an adjustment knob 5B and a locking screw 5C to apply friction on the threads or rod 5 as it passes freely through a cavity 8 in main supporting body at 1A. Rod 5 has secured thereto a cam 7 which is manually adjusted and so positioned on the rod by a pin 7A located on the cam 7 in the cavity 8 as to actuate a sensor or electronic

device to shut off the power to the production machine and indicate externally the measurement of the finish on the workpiece. The cam 7 actuates a linkage system 7B which by the means of a lever 7C thus it increases the movement of the system. The necessary electrical leads or conductors from the sensor device pass through the holes 8A and 8B to an external control and a measuring indicator. The electrical leads are connected to the external control by brushes and suitable leads not shown in FIG. 1 to the collector rings 26 and 26A. FIGS. 3 and 4 indicate the three holders 13 each are for retaining the honing members 14. Holders 13 each have two wedged shaped surfaces 13A and 13B and which surfaces engage the exterior tapered or wedged portion of discs 2 and 2A which discs are arranged to be threaded on rod 5 so that the surface of the wedged portion 13A and 13B ride upon longitudinal movement of rod 5 to expand the stones 14 in order to have the interior surface of the workpiece to be honed. The end portion 14A shows how the stones can extend beyond members 13 and 5D to hone blind interior surfaces.

In the operation of the mandrel of this invention before the actual of the operation by the production machine is started to hone a workpiece the following manual arrangements and adjustments are made on the honing tool.

First, three of the proper abrasive stones with the holders 13 are arranged to slide in the slots 1B as shown in detail in FIGS. 4 and 4A and slots 1C in the disc end member 4 shown at the far end of FIG. 1.

Second, referring to FIG. 4A one of the two retaining springs 6 is placed in groove 1B and the other one is placed in groove 1D and each spring is then placed over each end of holders 13 and held in position by grooves 13D.

Third, the three guide members 3C are interposed between each of the holders 13 and also retained by spring 6 thus holding the guide member 3C and abrasive members 14 nested together as shown in FIG. 3 to be in operative engagement without the use of any tools.

Fourth, the wedged disc 2 and 2A are moved or adjusted to a position on threaded rod 5 so as to bear against the larger cut away portions on the under side of members 13 as shown in FIGS. 1 and 4A. In this position the abrasive members will be in the position of the start of honing of the workpiece as indicated by dotted lines 33 shown by FIGS. 5 and 6.

Fifth, the cam 7 is then adjusted on control rod 5 so that the cam follower of the linkage system 7B rides on the lower or right hand portion of the cam and when it is in this position it is equal to the start of the honing of the workpiece as indicated by the dotted lines 33 in FIGS. 5 and 6. When this starting position is obtained the cam is secured to rod 5 by pin 7A.

Sixth, as the honing tool is now adjusted for the proper operation it is then secured at points A, B, C, and D as indicated at the forward portion of part 1 in FIG. 1 for rotation by the action of a production machine not shown.

Seventh, in order to keep the abrasive stones 14 expanded by the disc 2 and 2A riding against surfaces or in contact therewith 13A and 13B a forward motion is then provided by the production machine being secured at 5A to rod 5. As the rotation of the honing tool progress from the start of honing of the workpiece indicated by dotted lines 33 shown by FIGS. 5 and 6 to the finished position 32, the forward movement of rod 5 continues from the start position 33 to the finished position 32 by action of the disc 2 and 2A bearing against the cut away portions 13A and 13B to expand the honing member to engage the inner surface of a workpiece not shown. As the rod 5 also has cam 7 secured thereto in proper relation to each of the discs 2 and 2A. Then when the abrasive members have continued to be expanded by the forward action of disc 2 and 2A to the finished interior of the workpiece indicated by lines 32 the cam follower and linkage system 7B will have risen to the highest point on cam 7 to shut off the power of the production machine. When the power is shut off the rod 5 moves backward and springs 6 collapse and also the honing members 14.

A honing fluid or lubricant is applied to the stones 14 and guide members 3C which are interposed and nested between the abrasive members or stones.

As the honing operation proceeds as outlined above the cam 7 which has been manually positioned in proper alignment on rod 5 by pin 7A moves longitudinally to the right to a higher position so as to actuate the sensor device to indicate external measuring and control means through the linkage system 7B and lever 7C to shut off the power to the production machine to stop the honing operation. In one such electrical circuit method as referred to in FIG. 5 there is shown a variable capacitor 20 which is preferable in the form of a high dielectric constant type to provide a large change of electrical capacity so that a small mechanical movement of cam 7 thru the linkage 7B and 7C will provide a substantial change in the frequency of a tuned electrical high frequency circuit 21 which circuit may be in the order of 700 kc. and a change of 5 cycles for example will indicate a change in diameter of one one-thousandths of an inch, such a circuit also includes an inductance 22B preferably that of the iron core type. The iron core being indicated by numeral 23. The high frequency for circuit 21 is generated by a suitable frequency generator 21A the proper connections being made by the leads 27 and 28.

Another form of this invention is shown by FIG. 6 wherein the frequency of the tuned circuit may be changed by substituting a core 23A for capacitor 20 of FIG. 5. The frequency in this case being changed by the movement of the core 23A the features of this circuit will be explained in more detail later by changing the inductance of a coil 22A. The electrical conductors 24 and 25 of FIG. 5 pass through the holes 8A and 8B to a collector ring 26 and 26A which are also shown in FIG. 1. The other collector ring 26 may be omitted and connection may be taken off directly from the forward body portion of the mandrel. From the collector rings 26 and 26A there is connected by the leads 27 and 28 another variable capacitor 20A and an inductance 22B each of which form the other portion of the H. F. tuned circuit. Electrical connections 27 and 28 are then connected to an external amplifier circuit 29 outlined in block form. It is not necessary to show such a circuit in detail as such amplifiers are well known in the electrical art. The output from the amplifier circuit is connected by means of conductors 30 and 31 to a frequency meter 32 which may be of the type having a scale to indicate a change in the diameter of the workpiece. The finished interior surface of workpiece being indicated by dash lines 32 and the original unfinished interior surface being indicated by the dotted lines 33.

Referring now in detail to FIG. 6 there is shown the other electrical circuit mentioned above which also includes a portion of a high frequency circuit 34 in which the iron core 23A is actuated by cam 7 and linkage 7B to provide a change in the frequency of the circuit 21 which circuit is externally connected to a similar amplifier circuit 29. The output leads 35 and 36 which includes a battery not shown or electrical supply source which connects to an electrical relay 38. The relay 38 is so adjusted that when a frequency corresponding to a predetermined dimension of the internal diameter 32 of the workpiece is arranged to have conductors 39 and 40 shut off the power supply to the production honing machine and thus stop the honing of the finished workpiece.

I claim:

1. A honing machine of the type to be used in conjunction with a production honing machine which will apply both rotational and longitudinal motion to said mandrel, comprising a body member having located at one end thereof engaging means to be secured to the rotational motion portion of said honing machine, a control rod like member located within the central portion of said body member and having engaging means at one end thereof to engage the longitudinal portion of said honing machine, a plurality of rods secured to the end of said body member which is opposite the end of the engaging means and a plurality of radial slots in said last mentioned end of said body member, a disc like member secured to the far end of said rods to form a cage like structure and having a plu-

rality of radial slots in a similar angular relationship and facing the slots in the end of said body member, a pair of wedged disc members each adjustable secured to said control rod and having a serrated edge to permit their free passage on said rod, a plurality of abrasive members radially located within and having an upper edge extending beyond said rods, a holder for each of said abrasive members having their ends arranged to slide in said radial slots, and a pair of wedged slots located in the lower portion thereof so as to be in contact with the wedged edges of each of said wedged disc, a resilient member surrounding each end of each one of said abrasive holders to retain them in said radial slots and to be in operative engagement with the wedge edges of one of said disc to expand the abrasive members by the action of the longitudinal portion of the production honing machine on said control rod and the rotation of said body member by the rotational portion of the production honing machine to hone the interior surface of a workpiece.

2. A honing machine of the type to be used with a production honing machine which will apply both rotational and longitudinal motion to said mandrel, comprising a body member having a cavity portion and engaging means with the rotational portion of said production honing machine, a control rod located within the central portion of said body member and having engaging means at one end thereof to engage the longitudinal portion of said production honing machine, a plurality of abrasive members adjustable arranged at the far end of said control rod and said body member, a cam member adjustable arranged on said control rod at a position within said cavity portion, and electronic sensor device within said cavity portion and linkage means between said cam member and said sensor device to shut off the power to said production honing machine when a predetermined size is honed on a

workpiece.

3. A honing mandrel of the type to be used in conjunction with a production honing machine which will apply both rotational and longitudinal motion to said mandrel, comprising a body member having located at one end thereof engaging means to be secured to the rotational portion of said honing machine, a control rod like member located within the central portion and having engaging means at one end thereof to engage the longitudinal portion of said honing machine, a plurality of rods secured to the end of said body portion, a disc like member secured to the far end of said rods to form a cage like structure and having a plurality of radial slots in a similar angular relationship and facing the slots in the end of said body member, a pair of wedged disc members each adjustable secured to said control rod and having a serrated edge to permit their free passage on said rods, a plurality of abrasive members radially located within and having an upper edge extending beyond said rods, each of said abrasive members being of such a length as to have its far end extend beyond said disc like member to permit the honing of the interior surface of a blind hole in a workpiece, a holder for said abrasive members having their ends arranged to slide in said radial slots, and a pair of wedged slots located in the lower portion thereof so as to be in contact with the wedged edges of each said wedged disc, a resilient member surrounding each end of each one of said abrasive holders to retain them in said radial slots and to be in operative engagement with the wedge edges of each one of said disc to expand the abrasive members by the action of the longitudinal portion of the production honing machine on said control rod and the rotation of said body member by the rotational portion of the production honing machine to hone the interior surface of a blind hole in said workpiece.
